UNITED STATES PATENT OFFICE.

GEORGE PAUL THOMAS, OF GLENSHAW, PENNSYLVANIA.

TOOL-OPERATING MACHINE.

1,175,195.

Specification of Letters Patent. Patented Mar. 14, 1916.

Application filed December 28, 1914. Serial No. 879,275.

To all whom it may concern:

Be it known that I, GEORGE PAUL THOMAS, residing at Glenshaw, in the county of Allegheny and State of Pennsylvania, a citizen of the United States, have invented or discovered certain new and useful Improvements in Tool-Operating Machines, of which improvements the following is a specification.

10 My invention relates to tool-operating machines which are provided with work-carriages to bring to the tool, and by successive step-by-step advances, the material to be operated upon, means being provided 15 to advance the carriage, and stopping mechanism to arrest its movement at predetermined regular or irregular intervals.

The object of my invention is to improve the carriage driving and stopping mechanism.

20 A further and more specific object is to provide a machine wherein the work-carriage may be intermittently driven forwardly, uncontrolled by the stopping mechanism, and thereafter be yieldingly driven rearwardly to engage the stopping mechanism.

25 A still further object of my invention is to provide an efficient and inexpensive machine for punching holes in plates (particularly boiler and conduit plates) at substantially regular intervals.

In the accompanying sheets of drawings, which form part of my specification, I have 30 illustrated an embodiment of my invention as applied to metal-punching machines.

Figure 1 is a side elevation of the machine; Fig. 2 an end elevation thereof, the plane of view being indicated by the line II—II, Fig. 40 1; Fig. 3 a detail side view to enlarged scale of the driving connections and mechanism; Fig. 4 a sectional view taken on the broken line IV—IV, Fig. 3; Fig. 5 a sectional view taken on the line V—V, Fig. 4; and Fig. 6 45 a plan view of the driving pinions, the plane of view being indicated by the line VI—VI, Fig. 2.

In the several figures like numerals are used to designate like parts.

50 The punching machine may be of any suitable construction. That shown herein is particularly adapted for punching plates, and comprises a frame 1 provided with a reciprocating head 2, to which a pair of 55 punching tools 3 are secured. The head 2 is reciprocated in the usual and well known

manner by means of a rotary shaft 4, suitably connected to, or forming a part of a power shaft 5. Such shaft is provided with a pinion 6 meshing with a pinion 7 secured 60 to a shaft 8, which may be driven continuously in any desired manner. A further essential detail of the punching machine consists of dies 9 suitably secured to the frame 1 beneath the punching tools 3. The 65 work-carriage or spacing table may also be of any suitable construction. In the form shown herein the material to be punched, such as a plate 10, is borne upon a carriage 11, movable upon suitable tracks 12. 70

To the end that the construction of the machine may be simplified by the elimination of the usual stop-releasing mechanism, and to the further end that the stops will not be called upon to withstand the wear 75 and tear of relatively large impacts caused by the arrest of the carriage after it has been moved through a complete spacing interval, the carriage is intermittently advanced distances slightly greater than the 80 longest intended spacing interval, and is then given a reverse or rearward movement, the stopping mechanism being effective on such rearward movement to arrest the carriage at the desired point. Any suitable 85 stopping mechanism whereby such end may be attained may be used. In the present embodiment of my invention, suitably spaced stopping elements 13 are formed integrally with a metal bar 14 removably secured in any desired manner to support 15 disposed centrally between the tracks 12, 12. The stopping elements are regularly or irregularly spaced, and it will be understood that, in this arrangement, different bars 14 90 will be provided when necessary to punch plates having different spacing arrangements. The work-carriage 11 is provided at its rear end with a pawl 61, which, when the carriage is advanced or moved forwardly, 95 will ride over the stops 13, but which will be engaged by a stop on the rearward or reverse movement of such carriage. 100

While any suitable means may be employed to intermittently move the carriage 105 in the manner described, it is preferred to coördinate such movement with the reciprocation of the punch in such a manner that between each operation of the punch the carriage will be first advanced, and, at the 110 conclusion thereof, moved rearwardly to engage a stop. To such end, the carriage

may, as shown herein, be driven by suitable connections extending from, and operated by, the punching machine power shaft 5. Furthermore, the connections for effecting 5 the forward movement are preferably positive and unyielding, while the rearwardly-moving means are yielding and continue to act for a period after the movement of the carriage has been arrested thus absorbing 10 any tendency of the carriage to rebound, and holding the carriage firmly in position until the punches have entered the plate or other material to be punched.

In the illustrative embodiment of my invention, the carriage is driven by a rotary shaft 16, mounted in suitable bearings 25, 26, 27 and 28, and provided with pinions 17, 17^a adapted to mesh, respectively, with racks 18, 18^a, secured to the bottom of the 20 carriage. The shaft 16 is turned first in one direction and then in the other by means of pawl-and-ratchet connections shown particularly in Figs. 3 to 6, inclusive. However, it will be understood that pawl-and-ratchet 25 connections different than those shown herein may be employed, as well as other means for intermittently and alternately rotating the shaft 16 in opposite directions.

To drive the shaft to effect a forward 30 movement of the carriage, the end of the power shaft 5 is provided with a crank arm 19, to which there is adjustably secured a pitman 20, pivotally attached to an arm 21, rotatably mounted on the shaft 16. Pivotally secured to the arm 21 there is a pawl 23 adapted to engage the teeth of a ratchet wheel 24 keyed to the driving shaft 16. Means are provided to throw the pawl into and out of engagement with the ratchet 35 wheel, and to vary the intervals of such engagement: and, to hold the pawl in its alternate positions, it is provided with faces 29 and 30, against which the end of a thrust bolt 31 is yieldingly held by a spring 32. To 40 throw the pawl out of engagement with the ratchet, the pawl is provided with a finger 33 adapted to be tripped by a stop 34, adjustably secured to an arc-shaped frame 35, which frame is connected by means of brackets 36, 36^a to the shaft bearing-block 25. The pawl, when out of engagement with the ratchet, will extend in a general radial direction with relation to the center of the ratchet, and may be thrown to engage 45 the ratchet by means of a second stop 37 secured also to the frame 35. In the alternate engaging and disengaged positions of the pawl the bolt 31 bears against the faces 29 and 30, respectively; and it will be understood that the throwing of the pawl to 50 its alternate positions is effected by the arcuate movement of the arm 21.

The yielding pawl-and-ratchet connection for turning the shaft 16 in the opposite 65 direction is similar in its general construc-

tion to that just described. The power shaft 5 is provided with a pinion 38, which meshes with a second pinion 39, rotatably mounted on the punch frame 1. To the pinion 39 there is pivotally secured a pitman 40, either 70 directly, as shown, or adjustably as in the case of the pitman 20. The pitman 40 is also pivotally secured at its opposite end to an arm 41 rotatably mounted on the shaft 16. A driving member, including a ratchet 75 wheel 43 and one member of a friction clutch, is also rotatably mounted on such shaft. Said friction clutch member consists of a casing 44, rotatably mounted on the shaft 16, and which has secured thereto a 80 plurality of plates 45. The second clutch member consists of a second series of plates 46, arranged alternately with the plates 45, and secured to a collar 47, keyed to the shaft 16. The plates are, as shown, held in 85 frictional contact with each other by means of adjustable springs 48. To the arm 41 there is pivoted a pawl 49, held yieldingly in engagement with the ratchet by means of a spring 50, and provided with a roller 51, 90 adapted, during such time as the pawl is to be held from engagement with the ratchet, to run on a cam or track 52. This track may be adjustably secured, as by means of bolts and slots to a suitable support 42, attached 95 in turn to the shaft bearing block 26.

The machine shown herein may be used for punching material in all cases wherein no single spacing interval is as great as the sum of any two adjacent intervals. In setting or adjusting the machine when it is intended to punch at irregular spacing intervals, a bar 14 having stops 13 spaced at the desired intervals is secured in proper position to the support 15. The driving mechanism for the advance movement of the carriage is then adjusted to move the carriage forwardly, upon each revolution of the power shaft, a distance slightly greater (say one quarter of an inch) than the longest 100 spacing interval. Also, the reverse driving mechanism is adjusted to effect a return movement of the carriage a distance slightly greater than the maximum necessary reverse movement. As for example, if the maximum spacing interval were 5 inches and the minimum interval 3 inches, the mechanism for advancing the carriage should be set to drive the carriage more than 5 inches (say 5 $\frac{1}{4}$ inches), but not as much as 6 inches; and if the advance were set for 5 $\frac{1}{4}$ inches the return movement should be set for a distance greater than the difference between 5 $\frac{1}{4}$ inches and 3 inches, or a distance greater than 2 $\frac{1}{4}$ inches. Such adjustments may be accomplished by varying the distance of the point of attachment of the upper end of the pitman 20 from the center of the shaft 5, and adjusting the stop 34 and the track 52. However, since boiler plates, and the like, 115 120 125 130

are usually punched with evenly spaced holes, the stop plate 14 for such purpose will have evenly spaced stops 13, and the complications of setting up or adjusting the carriage driving mechanism will therefore be eliminated.

In the operation of the machine the movable parts are so coördinated with the rotation of the power shaft 5, that, during the 10 upward movement of the punching head, and after the punches have been withdrawn from the material being punched, the connections for driving the carriage forwardly become effective. These connections are, 15 from the power shaft, through crank arm 19, pitman 20, arm 21, pawl 23, ratchet 24, shaft 16, pinions 17, 17^a and racks 18, 18^a; and such driving connections continue to act until the finger 33 of the pawl 23 strikes 20 the stop 34 and causes the pawl to be disengaged from the ratchet. Meanwhile the carriage will have been advanced so that the carriage-stopping pawl 61 will be a distance beyond a stop 13. At this point of 25 the rotation of the power shaft the pawl 49 of the rearwardly driving connections has, through pinion 39, pitman 40 and arm 41, been moved off the track 52, and hence into engagement with the ratchet 43. The continued rotation of the power shaft then 30 drives the carriage rearwardly through the friction clutch; and such rearward driving continues to act (the clutch plates slipping) after the carriage pawl 61 has engaged a 35 stop 13, thus absorbing the rebound of the carriage and holding the carriage firmly until the punches again engage or enter the plate. Near the end of the inactive stroke of the pitman 20 the pawl 23 will strike 40 the stop 37 and be thereby thrown to ratchet-engaging position for the next active stroke of such pitman, but, before such stroke begins, the pitman 40 will have moved to such point that the pawl 49 will 45 be disengaged from the ratchet 43. The cycle of operation thus described is repeated intermittently and automatically during each revolution of the continuously rotating power shaft 5, and until a complete 50 line of holes has been punched.

I claim as my invention:

1. In a tool-operating machine, the combination of a work-carriage, stopping mechanism effective to arrest a rearward movement of said carriage, unyielding means for effecting a forward, and yielding means for effecting a rearward movement of said carriage.

2. In a tool-operating machine, the combination of a movable work-carriage, means for effecting a step-by-step advance of said carriage, means for effecting a rearward movement of the carriage after each advance thereof and a distance less than such advance, and means for varying the effec-

tive lengths of said advance and rearward movements of the carriage.

3. In a tool-operating machine, the combination with a tool, a work-carriage, and a power shaft; of tool-operating connections between said shaft and tool, stopping mechanism effective to arrest a rearward movement of said carriage, unyielding means for effecting a forward, and yielding means for effecting a rearward movement 75 of said carriage.

4. In a tool-operating machine, the combination of a movable work-carriage, a plurality of spaced stopping elements effective to arrest the rearward movement of said carriage, unyielding means for effecting a forward, and yielding means for effecting a rearward movement of said carriage, said rearwardly-moving means acting, after the stopping of the carriage, to resist the rebound thereof. 80

5. In a tool-operating machine, the combination of a movable work-carriage, a continuously rotatable power shaft, a carriage-driving shaft operatively connected to said carriage, operative connections from said power to said driving shaft to intermittently rotate the latter in one direction, and operative connections from said power to said driving shafts to rotate the latter in 90 an opposite direction, said last mentioned driving connections becoming effective immediately upon the first named driving connections becoming ineffective.

6. In a tool-operating machine, the combination of a movable work-carriage, means including a rotary shaft for moving said carriage, means for driving said shaft in one direction, means including a yielding connection for driving said carriage in an 105 opposite direction, each of said driving means being ineffective while the other is effective to drive the shaft.

7. In a tool-operating machine, the combination of a movable work-carriage, means including a rotary driving shaft for moving said carriage, a continuously rotatable power shaft, pawl-and-ratchet connections between said shafts for intermittently and alternately rotating the driving shaft in 110 opposite directions.

8. In a tool-operating machine, the combination of a movable work-carriage, means including a rotary driving shaft for moving said carriage, a continuously rotatable power shaft, a pair of pawl-and-ratchet connections between said shafts for intermittently and alternately rotating the driving shaft in opposite directions, and means for throwing one of the pawls from engagement with its ratchet while the other pawl is in engagement with the other ratchet. 120

9. In a tool-operating machine, the combination of a movable work-carriage, means including a rotary driving shaft for moving 125

- said carriage, a continuously rotatable power shaft, a ratchet wheel secured directly to said driving shaft, a pitman movable by said power shaft and provided with a pawl 5 adapted to engage said ratchet, means effective upon the movement of said pitman to throw said pawl into and from engagement with said ratchet, and operative connections between said shafts to rotate the driven 10 shaft in a direction opposite to its rotation by said pawl-and-ratchet connection, said last named connections including a yielding member.
10. In a tool-operating machine, the combination of a movable work-carriage, means including a rotary driven shaft for moving said carriage, a driving member rotatably mounted on said shaft and provided with a ratchet wheel and with a yielding clutch 15 member, a second clutch member secured to said shaft and engaging the first named clutch member, a continuously rotatable power shaft, a pitman movable by said power shaft and provided with a pawl 20 adapted to engage said ratchet to move said driving member in one direction, and operative unyielding connections between said shafts to rotate the driven shaft in a direction opposite to its rotation by said pawl-and-ratchet connection.
11. In a metal-punching machine, the combination with a punch, a movable work-carriage, and a power shaft; of punch-reciprocating connections between said shaft and punch, a plurality of spaced stopping elements, a rotatable carriage-driving shaft, unyielding pawl-and-ratchet connections between said shafts to intermittently move 25 said carriage forwardly a distance greater than the interval between adjacent stopping elements, yielding pawl-and-ratchet connections between said shafts to effect a reverse movement of said carriage upon the 30 conclusion of the action of said forwardly moving connections, and means to cause said stop to arrest the reverse movement of the carriage before the conclusion of the action of said yielding pawl-and-ratchet driving connections.

In testimony whereof I have hereunto set my hand.

GEORGE PAUL THOMAS.
